Filed Apr. 17, 1963, Ser. No. 74,477

Term of patent 14 years

(Cl. D48—27)

FIG. 2

FIG. 1

FIGURE 1 is a front perspective view of a cigarette lighter illustrating my new design; and

FIGURE 2 is a top plan of the cigarette lighter.

The undisclosed side of the upper housing is substantially the same in appearance as the side shown, the undisclosed sides of the base are identical to the sides shown, and the bottom is flat and plain.

The parallel lines on the circular elements near the top and in the center of the lighter housing represent conventional grooves.

I claim:

The ornamental design for a cigarette lighter, as shown and described.
